JAMES M. JOHNSON AND JOHN HERIG, OF CLEVELAND, OHIO.

Letters Patent No. 82,004, dated September 8, 1868.

IMPROVEMENT IN MORTISING-MACHINES.

The Schedule referred to in these Letters Patent and making part of the same.

TO ALL WHOM IT MAY CONCERN:

Be it known that we, JAMES M. JOHNSON and JOHN HERIG, of Cleveland, county of Cuyahoga, in the State of Ohio, have invented a new and improved Sash-Mortising Machine; and we do hereby declare that the following is a full and exact description thereof, reference being had to the accompanying drawings, and to the letters of reference marked thereon.

Figure 1 is a front elevation.

Figure 2 is a plan view.

Figure 3 is a detached section of the driving-pulleys.

Figure 4 is a detached section of the chisel-holder.

Figure 5, section of the ratchet and pinion for moving the bed

Figure 6, section of cross-head, showing the bearings.

Figure 7, section showing the connection between the treadle and sliding-pulley box.

The nature of this invention relates to the construction and arrangement of a mortising-machine, for mortising sash-stiles in a more expeditious and perfect manner than is now done by the ordinary means, and consists in the manner of arranging the guides or rests and bed upon which the stiles are placed, their adjustability, and the perfection of the work done; also, in the manner of attaching and arranging the chisel-holders upon the cross-head, so that they shall perfectly retain their perpendicular position and still be readily shifted upon the same, to accommodate them to different widths of stiles.

The driving-pulleys at the top of the machine are placed in a sliding box, which is operated by the foot-treadle, to bring the cross-head down to the work.

The bearings or slides for the play of the cross-head are so constructed that whenever they become worn they may be tightened, and so kept in good working order.

Upon the frame and standard A, which may be of cast iron, of suitable strength and proportions, is arranged the machinery comprising our improvements.

On the front and near the sides of the frame A are cast the projections or ways *a a*, for supporting the sliding bed B, figs. 1 and 2. This bed is provided, at each end, with a V-shaped groove, *a'*; which rests upon a corresponding V-shaped tongue upon the ways *a a*.

Upon the top of said bed B are arranged the guide-rests *c c*, which are constructed with slots, through which the thumb set-screws *c' c'* pass into the bed B, for the purpose of securing the guides in a position suitable to the different sizes of stiles.

The guide-rests *c c* have upon their inner ends a stop, *d*, arranged with set-screws *d'*, to adjust them to the various thickness of stiles, which serve to hold the stiles down in place while the machine is in operation.

There are also springs *e e* placed upon said bed B, to hold the stiles up against the guides *c c*.

In front of the bed B is arranged a projection or arm, D, seen in detached sections, fig. 5, to which is attached a hand-wheel, *f*, which carries the pinion *g*, said pinion meshing and working with the ratchet *h*, said ratchet being made on the under-side of arm *D'*, projecting from and secured to the frame A.

Upon the top of said arm *D'* is placed a slotted strip, *i*, secured by a set-screw, *k*. Upon the side of said arm *D'* is a similar strip, *i'*, and set-screw *k'*. These, which may set as desired, are intended to determine the length of the mortise.

E is a cross-head, having a slot, *E'*, in which are arranged the chisel-holders *F F*, seen also in fig. 4.

In the under side of the cross-head is cut a groove, *n*, the chisel-holder having a corresponding tongue, *n'*, which fits the said groove. The chisel-holders also have a projection, *O*, which fits the slot *E'*.

A screw, *p*, having a head and shoulders, *p'*, which also fits the slot *E'*, passes through the chisel-holder *F*, and a thumb-nut, *q*, secures the same firmly in place.

The shanks of the chisels are slightly tapering, and fit into corresponding sockets in the chisel-holders. The object of this mode of constructing and arranging the chisel-holders is to insure their permanency in an upright position, and yet they may be easily and readily shifted as occasion may require.

The bearings t and t' of the slides of the cross-head are triangular or V-shaped, so that whenever they become worn they may be tightened by setting up the screws u u in the same.

The driving-pulley is located on the top of the standard A. There is a wheel, r , upon the same shaft, and is connected with the cross-head by the connecting-rod r' . The journals of this shaft are seated in the sliding boxes x x , said boxes being enclosed in the framework y y , and are connected by the rod z to the foot-treadle z' , by which means the cross-head is made to approach the work.

To keep the cross-head up from the work, a lever, L, is hung in the frame A, having a weight, m , attached to the long arm, the short arm being attached, by a double joint, to the pulley-boxes. The said weight m , over-balancing them, keeps the pulleys and cross-head up.

The chisels are bevel-sided, to suit the different-shaped mortises, as they are to be made in the sash-stiles, the centre chisel being made to cut the inner mortise of the stiles.

When this is to be done, the guide-rests c c are to be moved back, as seen in dotted line, fig. 2, and a small strip, B', placed upon the bed B, and having bevelled groove cut into it to fit and hold the bevelled cross-bars of a window-sash.

Attached to the ways a a of the frame A, and opposite to the ends of the bed B, are adjustable stops b b' , which serve as guides for placing the cross-bars when they are to be mortised.

What we claim as our improvement, and desire to secure by Letters Patent, is—

The chisel-holders F F, constructed as described, in combination with the cross-head E, to operate as and for the purpose set forth.

JAMES M. JOHNSON,
JOHN HERIG.
